UNITED STATES PATENT OFFICE.

GEORGE P. CLARK, OF NEW YORK, N. Y., ASSIGNOR OF ONE-HALF TO
E. MANN VYNNE, OF NEW YORK, N. Y.

STEAM-ENGINE.

SPECIFICATION forming part of Letters Patent No. 740,089, dated September 29, 1902.

Application filed March 1, 1902. Renewed April 6, 1903. Serial No. 151,413. (No model.)

To all whom it may concern:

Be it known that I, GEORGE P. CLARK, a citizen of the United States, residing at New York, in the county and State of New York, have invented certain new and useful Improvements in Steam-Engines, of which the following is a specification.

This invention relates to steam-engines, and particularly to those of a low-speed type, and has for its object to provide an improved steam-engine of the class described in which there is a direct continuous exertion of the power and in which there is no dead-center.

In the drawings, Figure 1 is a central longitudinal sectional view of a cylinder and piston embodying my improvements. Fig. 2 is a sectional view on the line $x-x$, Fig. 1. Fig. 3 is a plan view of the same. Fig. 4 is a side elevation of the same. Fig. 5 is a sectional view on the line $x-x$, Fig. 4. Fig. 6 is a sectional view on the line $x-x$, Fig. 5, with parts broken away. Fig. 7 is a side elevation showing a modification of certain parts of the invention. Fig. 8 is a detail view of a portion 25 of the chain and one of the rollers.

Corresponding parts in all the figures are denoted by the same reference characters.

Referring to the drawings, 1 designates a cylinder having extended from its heads 2 hollow sleeves 3. The cylinder 1 may be supported in any suitable manner. A piston-head 4 works in the cylinder 1 and is provided with the usual packing 5. The piston-head 4 has an opening 6, bored transversely through such head, which opening 6 is internally screw-threaded for a distance from each end. A plug 7 screws in each end of said opening and is provided with a rectangular recess 8 in its lower part. The inner wall of such recess 8 at the top is case-hardened. Extending through the central portion of the piston-head 4 in alignment with the opening 6 are two spaced openings 9, through which a sprocket-chain 20 passes. Surrounding said chain 20 and extending from each side of the piston-head 4 is a hollow cylindrical sleeve 11, which passes into the sleeve 3. Bored centrally through the piston-head 4 is a hole 12, one end of which is of smaller diameter than the remainder of said hole 12. A shaft 13 passes through said hole 12 and has its end journaled in the por-

tion of the hole 12 of smaller diameter and carries an enlarged cylindrical portion 14, the outer surface of which is inclined at angle to the axis of the shaft 13. A cap 15 forms a bearing for the shaft 13 on the opposite side of the enlargement 14 and is secured in place by set-screws passing through the piston-head transversely to the opening 6. The shaft 13 extends outwardly from the piston-head 4 through one of the hollow sleeves 11 and has a bearing near its end in a plate 16, secured across the end of the sleeve 11. A small gear 17 is mounted upon the end of the shaft 13. The plate 16 extends at one side through a longitudinal slot 18 in the side of one of the sleeves 3. Mounted at the outer end of the plate 16 is a wheel 19, operated by a handle 20 and having on a portion of its periphery teeth 21. Mounted upon the plate 16 is an idler-gear 22, which meshes with the gear 17 and the toothed portion of the wheel 19. The chain 20 has one surface smooth which bears against the enlargement 14 and the other surface substantially corrugated transversely or having spaced inequalities therein, which uneven surface is in engagement with the rollers 23, which are seated in the recesses in the plugs 7. Suitably mounted with reference to the ends of the sleeves 3 are shafts 24, carrying sprocket-wheels 25, over which the chain 20 passes. One of the shafts 24 also has the driving-wheel 26 mounted thereon. Idlers 27 are suitably mounted to guide the chain 20 into the sleeves 11. The cylinder 1 is provided at each end with an opening 28, from which a pipe 29 leads to a four-way valve 30, connected by a pipe 31 with a suitable steam-supply (not shown) and with a suitable exhaust-chamber (not shown) by a pipe 32. Means are provided for operating the valve 30 to open communication between the steam-pipe 31 and the opening 28 at one end of the cylinder at the same time that communication is opened between the opening 28 at the other end of the cylinder and the exhaust-pipe 32. Such means are here shown as a tube 33, slidably mounted at the side of the cylinder 1 and closed at one end and having a plunger 34 slidably mounted and working through the other end. Adjustably se-

cured upon the tube 33 is a collar 35, the lower end of which moves in a guideway 36, provided at either end with suitable cushion-stops 37. The collar 35 is connected by a link 38 with the valve-stem 30^a by a pin-and-slot connection. The tube 33 is provided with air-holes 39 and with a loosely-mounted sleeve 40, provided with a thumb-screw and adapted to close the air-holes 39. One end 10 of the plunger 34 is secured to the outer end of the plate 16.

A modified form of the invention is shown in Fig. 7, in which there are two cylinders 41 and 42, each of which is open at one end and has 15 a hollow sleeve projecting from only one end. The cylinders 41 and 42 are placed with their closed ends adjacent, the hollow sleeve of one projecting parallel with the body portion of the other. It is evident that in this construction 20 the chain 20 will pass only once through each of the cylinders, and therefore only one opening 9 through the piston-head and one roller 23 will be necessary for each piston-head 4 and that there will be only one hollow sleeve projecting from said piston-head. The advantage 25 of this modified form of construction is that the chain 20 can be led through the cylinders 41 and 42 into planes substantially tangentially to the periphery of the sprocket-wheels 25.

The operation and advantages of my invention are readily appreciated and understood. The parts being in the position shown in Fig. 1, steam is turned on, and entering the cylinder 1 through the valve 30 and pipe 29 drives the head 4 toward the opposite end of the cylinder 1. As the head 4 moves in that direction the upper span of the chain 20 is gripped between the roller 23 and the surface 40 of the enlargement 14 and carried along with the head 4. The head 4 also carries the sleeve 11 and shaft 13, and hence the plate 16, by means of which latter the plunger 34 is drawn forward and moves the tube 33, closing 45 the communication between the steam-pipe 31 and the opening 28, which had previously been open, and opening that between the steam-pipe 31 and the opening 28 at the other end of the cylinder 1. This moves the head 4 in the opposite direction. To reverse the movement of the chain 20, it is only necessary to give the toothed wheel 19 and the shaft 13 a half-turn, thereby changing the direction of the incline of the enlargement 14 in the openings 9.

I do not desire to be understood as limiting myself to the details of construction and arrangement as herein described and illustrated, as it is manifest that variations and 60 modifications may be made in the features of construction and arrangement in the adaptation of the device to various conditions of use without departing from the spirit and scope of my invention and improvements. I

65 therefore reserve the right to all such variation and modification as properly fall with-

in the scope of my invention and the terms of the following claims.

Having thus described my invention, I claim and desire to secure by Letters Patent— 70

1. The combination with an engine-cylinder, of a hollow piston-rod, a piston having parallel channels therethrough intersecting recesses in the piston, rollers in said recesses, and a gripping device rotatably mounted 75 within the piston, and coöperating with said rollers.

2. The combination with an engine provided with a cylinder and a hollow piston-rod working in said cylinder, of a piston-head having two parallel channels therethrough, recesses adjacent to said channels, rollers in said recesses projecting into said channels, and a longitudinally-inclined cylindrical surface 85 rotatably mounted in said head between said channels and forming part of each.

3. In an engine provided with a cylinder and a hollow piston-rod, a piston-head provided with two channels, recesses opening into said channels, rollers in said recesses and 90 projecting into said channels, and a longitudinally-inclined cylindrical surface rotatably mounted between said channels and forming part of each, and means for rotating said surface.

4. The combination with an engine-cylinder, of a hollow piston-rod, a piston having parallel channels therethrough intersecting recesses in the piston, rollers in said recesses, and a rotatable inclined cylindrical gripping 100 device coöperating with said rollers.

5. In an engine provided with a cylinder and a hollow piston-rod, a piston-head provided with two channels, recesses opening into said channels, rollers in said recesses and projecting into said channels, and a longitudinally-inclined cylindrical surface 105 rotatably mounted between said channels and forming part of each; a shaft connected with said cylindrical surface and extending through said piston-rod and provided at its end with a gear; and a handle carrying a gear meshing with said shaft-gear.

6. In an engine, a cylinder having one end open, and a hollow piston-rod working therein and provided with a head having channels therethrough, recesses containing rollers projecting into said channels and an inclined plane forming the wall of said channels opposite said rollers. 115

7. The combination with motor mechanism, of a pair of wheels, cylinders between said wheels, hollow piston-rods operable in said cylinders and provided with heads having channels therethrough with a roller on one side and an inclined plane on the other, and a drive-belt passing over said wheels and through said channels and piston-rods and adapted to be gripped between said rollers and said inclined planes. 125

8. In combination with mechanism embodying a pair of spaced wheels and a cylin-

- der between said wheels, a hollow piston-rod operable in said cylinder and provided with a head having channels therethrough, recesses at the sides of said channels with rollers therein and inclined surfaces on the sides of said channels opposite said rollers; and a sprocket-chain passing over said wheels and through said channels between the rollers and inclined planes.
10. 9. In an engine, comprising a pair of wheels and a cylinder between them, a hollow piston-rod operable in said cylinder and provided with a head having channels therethrough and recesses having rollers therein at the sides of said channels and inclined planes opposite said recesses, and a sprocket-chain passing over said wheels and through said channels, and adapted to be gripped between the rollers and the inclined planes.
15. 10. In an engine, comprising a pair of wheels, a cylinder between said wheels, and a hollow piston-rod operable in said cylinder, a piston-

head having channels therethrough and bored transversely to said channels to form seats for rollers and longitudinally between said channels to mount a rotatable shaft having an enlarged portion with its exterior surface inclined to the axis of the shaft and forming one side of said channels.

11. In an engine provided with a piston-head having channels therethrough with rollers on one side and an inclined surface on the other, a sprocket-chain passing through said channels and having the surface toward the inclined plane smooth and the surface 35 toward the rollers provided with transverse depressions.

In testimony whereof I have signed my name in the presence of the subscribing witnesses.
